COMBINED FAUCET AND AIR PUMP FOR
LIQUID CONTAINERSAlexander Henry Welker, Waterloo,
Ontario, Canada

Application April 14, 1934, Serial No. 720,526

7 Claims. (Cl. 225—16)

My invention relates to improvements in combined faucets and air pumps for liquid containers, and the object of the invention is to incorporate a faucet and air pump into a single unit, in which 5 the pump and faucet will be alternately operable and simultaneously inoperable to prevent leakage, in which the faucet, when secured in the container, can be tightened in any position desired in relation to the tap, which may be used in any 10 depth of container, which can be sealed to render it impossible to remove the container contents without breaking the seal, and in which the pump, when the pump and spout are sealed in the closed position, coats with a half cover to 15 form a handle grip, and it consists essentially of the arrangement and construction of parts as hereinafter more particularly explained.

Fig. 1 is a sectional elevation of my device taken through the pump.

20 Fig. 2 is a sectional view on line 2—2, Fig. 1.
Fig. 3 is a sectional plan view on line 3—3, Fig. 1 or 2.

Fig. 4 is a sectional view through the upper portion of a cask and showing my device in elevation.

25 Fig. 5 is a plan view of a cask showing my device on a reduced scale with the half cover broken away from the most part.

Fig. 6 is an enlarged perspective detail showing two fragmentary portions of the cover and the engaging means between one end of the cover 30 and cask head.

Figs. 7 and 8 illustrate a modified form of sealing means.

35 Fig. 9 is a sectional view of the lower end of the liquid discharge pipe showing the strainer sieve.

Figs. 10, 11, and 12 indicate alternative structures for preventing the use of the spout as a handle and the consequent breaking of the same.

40 In the drawings like characters of reference indicate corresponding parts in each figure.

1 indicates a cask provided with the usual end head 2 having an orifice 3 in which is screwed a cylindrical bung 4 having an externally threaded head 5 having a tapered lower face countersunk in the surface of the head 2 and a circular recess 5× in the upper face. 6 is a nut which is recessed on its lower face at 6× and internally threaded and provided with a central orifice 60. 7 is the 45 body of the faucet provided with a circular base 7× slightly thicker than the depth of the recess 5× so that its upper face is above the upper edge of the recess wall permitting of the base 7× being clamped between the top wall of the nut and the 50 base of the recess 5×.

8 is a transverse tapered orifice in the body 7 forming a seat for the valve plug 9. 8× is an air port extending from the orifice 8 to the bottom of the base 7× within the open centre of the bung 4 and 8° is an orifice also extending from the orifice 8 to the bottom of the base 7× and in which is secured the upper end of the liquid discharge pipe 10, passing through the open centre of the bung 4 into the liquid container such as the cask 1 and extending adjacent the bottom thereof. The 10 plug 9 is provided, at its outer or large end, with a cylindrical enlargement 11 forming an annular shoulder 11× bearing against the wall of the body 7 around the orifice 8.

The small end of the plug 9 projects from the 15 small end of the orifice 8 and is threaded as indicated at 12. 13 is a nut which is screwed onto the threaded portion 12 and 13× is a compression spring extending between the nut 13 and the opposing wall of the body 7 to resiliently hold the 20 plug 9 from free rotation. 110 is a boss extending from the periphery of the plug enlargement 11. The boss 110 is provided with an internally threaded orifice 111. 9× is a duct leading from the orifice 111 and located, at its opposite end, in 25 the periphery of the plug 9 at a point in circumferential alignment with the air port 8×. 90 is a liquid discharge duct extending from the periphery of the plug 9 in circumferential alignment with the adjacent end of the liquid discharge 30 pipe 10. 91 is a lateral extension of the orifice 90 extending centrally through the small end of the plug 9 and in which is secured the inner end of a spout 14.

It will thus be seen that there is an angle of 35 90° between the position of the port orifices 8× and 8° of the body and the normal position of the discharge end of the air duct 9× and also an angle of 90° between the normal position of the discharge end of the air duct 9× and the liquid 40 discharge orifice 90.

14× is a pump base member having a reduced exteriorly threaded portion 140 having a central orifice 15, one end of which is enlarged at 15× to receive a ball valve 16 coacting with a seat 16× 45 at the inner end of the enlargement, the opposite end having a slightly burred edge to retain the ball therein. The opposite end of the orifice 15 is also enlarged at 15× to receive the tubular piston rod 17 which is secured therein carrying 50 a piston 17×.

18 is a pump cylinder open at its inner end to slidably fit the reduced exterior portion 151. Within the cylinder is screwed an inner head 18× 55

having an orifice 18^0 through which the piston rod 17 slidably extends.

From the foregoing it will readily be seen that when the pump cylinder 18 is swung through 90° together with the spout 14 to a vertical position that the outer ends of the ducts 9^x and 9^0 will travel down 90° so that the duct 9^x registers with the upper end of the port 8^x , the duct 9^0 leading to the spout remaining closed. The pump is then operated to pump air into the top of the container over the liquid to produce a pressure thereon.

If it is desired to draw the liquid, the pump 18 is swung together with the spout a further 90° carrying the spout and duct 9^0 into position to register with the upper end of the discharge pipe 10 at the same time carrying the duct 9^x to a closed position. The liquid, by means of the air pressure previously created in the container, forces the liquid up the pipe 10 through the duct 9^0 and the spout 14 . The parts, during the liquid out-flow, assume the dotted position shown in Fig. 5 enabling the discharged liquid to be received in a suitable receptacle. When the pump is swung back to the normal position shown in Fig. 1 both ducts 9^x and 9^0 are in the closed position, the pump and spout being then in position ready for sealing.

19 is a half cover formed preferably of sheet metal bearing at its edge against the rim of the container as shown in Figs. 4 and 5 and bearing also against the pump cylinder 18 , the edge of the cover being curved downward at 19^x to follow the contour of the pump cylinder.

To secure the cover in place, I provide a looped bracket 20 depending from the cover and a bracket 21 secured to the container head 2 and forming a tongue 22 engaging the bracket 20 . 23 is an orifice adjacent the opposite end of the cover through which a stud 24 forming part of the valve body 7 projects. Around the orifice 23 the cover is depressed as indicated at 24^0 to provide room for a perforation 24^x through which a sealing wire 25 extends without projecting above the rim 2^x of the cask or container. 26 is a seal for sealing the ends of the wire 25 .

The cover 19 not only protects the faucet and pump from injury, but prevents its operation by an unauthorized person and also serves in conjunction with the pump cylinder as a comfortable and strong hand grip for lifting the container from place to place.

In Figs. 7 and 8 I show an alternative form of sealing means. In these figures the stud 24 is provided with a peripheral notch 26 . 27 is a plate pivoted at 28 , an edge of the plate extending through the notch 26^0 after being sprung over the head of a rivet 29 . A sealing wire 30 passes through a perforation 31 and a corresponding perforation formed in the cover 19 .

The pipe 10 is formed of bendable material so that its length may be accommodated to any depth of cask by off-setting it as indicated in Fig. 4. The pipe 10 is also provided with a sieve 32 to prevent any sediment or other foreign matter passing up the pipe with the liquid.

In Fig. 10 I have shown a modified form of spout connection which will allow of the spout being secured in a stationary position during pouring and at the same time prevent it being used as a handle for lifting the keg or container from place to place. If the spout was rigidly connected to the valve plug 9 as in Fig. 3, the operator might attempt to lift the can by carelessly gripping the spout and breaking it. To

avoid this result, I couple the spout 33 to the externally threaded discharge end of the valve plug 34 .

35 is a nut screwed at one end upon the thread of the valve body and freely surrounding the spout at the opposite end. An internal shoulder 35^x is formed between which and the end of the valve plug the annularly flanged end 33^x of the spout 33 and a packing washer 35^0 is clamped forming a leak proof joint which will allow the spout to turn freely in the nut 35 so that no lifting strain can be put on it tending to break it off.

In Fig. 11 I show another modified form which achieves the same result as that of Fig. 10. In this form the spout 36 is made of flexible metal tubing secured to the discharge end 37 of the valve plug by welding or other suitable means.

In Fig. 12, if any lifting strain is exerted on the spout, it automatically separates from the valve plug. In this form the inner end of the spout is provided with a bayonet slot or slots 38 with which a corresponding pin 39 engages, the pin extending from the plug discharge end 40 . Any upward lift on the free end of the spout engages the curved portion of the slot 38 with the pin 39 producing a cam action which forces the spout outward longitudinally from the discharge and clear of the pin 39 .

In the forms shown in Figs. 10 and 11, the free end of the spout may be secured to the container so that it will remain in a stationary position and not move back and forth every time the device is operated to shut off the liquid and thereby make it more convenient to draw liquid from the container.

From this description it will be seen that I have devised a device, particularly adaptable to beer casks, in which a faucet and pressure pump are incorporated in one unit, in which it is ensured that when the port of one of the aforesaid devices is open for operation the port of the other device is positively closed or when both devices are not in operative position the ports of both devices are positively closed so that under no condition can leakage occur, and in which the position of the spout is not controlled by the final position of the bung in the bung orifice so that the spout, in its inoperative position, will lie adjacent the inner side of the container rim and in the operative position will project, at its pouring end, over the container rim in position for pouring, and in which the parts may be effectually sealed from use, protected from injury when sealed and form a convenient means for lifting the container from place to place, and which may be readily adapted for use in any depth of cask or container.

What I claim as my invention is:—

1. The combination with a faucet body having a conical valve seat, a liquid port and an air port extending from the seat to the bottom of the body, a conical valve engaging the seat, a pump mounted on one end of the valve and a spout mounted on the opposite end, and ducts in the valve respectively alternately connecting the pump to the air port and the liquid port to the spout.

2. The combination with a faucet body having a conical valve seat, a liquid port and an air port extending from the seat to the bottom of the body, a conical valve engaging the seat, a pump mounted on one end of the valve and a spout mounted on the opposite end, ducts in the valve

respectively alternately connecting the pump to the air port and the liquid port to the spout, and a non-return valve located between the pump and air duct of the valve.

5. 3. The combination with a container having a rim forming a depressed head, of a faucet, a pump mounted on the faucet to swing from a vertical to a horizontal position, a cover engaging the rim at its circumferential edge and the pump diametrically, and securing means adapted to be sealed for securing the cover in place and comprising a loop depending from the cover, a tongued member secured to the head and engaging the loop at a point diametrically opposite to the faucet, a projection located adjacent the faucet and passing through the cover and perforated adjacent its upper end to receive a sealing wire.

4. In a faucet for liquid containers, the combination with the faucet body and faucet plug having coacting liquid and air ports, of a discharge spout connected to the discharge of the plug and capable of being held in a stationary position at one end without interfering with the free turning movement of the valve plug at its opposite or connected end.

5. The combination with a container having a rim forming a depressed head, a faucet, a pump mounted on the faucet to swing from a vertical to a horizontal position, a segmental cover en-

gaging the rim at its circumferential edge and the pump at its diametric edge, and engaging means at one end of such diametric edge between the cover and container head, and a sealing means for securing the cover to the valve body at the other end of the diametric edge.

6. The combination with a container having a rim forming a depressed head, of a faucet, a pump mounted on the faucet to swing between a vertical and horizontal position, a cover engaging the rim at its circumferential edge and the pump diametrically, securing means adapted to be sealed for securing the cover in place and comprising means for sealing the cover to the faucet body, and engaging means comprising a loop depending from the cover and a tongued member secured to the head and engaging the loop at a point diametrically opposite to the faucet.

7. The combination with a container having a rim forming a depressed head, a faucet, a pump mounted on the faucet to swing between a vertical and horizontal position, a cover engaging the rim at its circumferential edge and the pump diametrically, engaging means between the cover and container head at a point adjacent the diametric edge and remote from the faucet, and a projection located adjacent the faucet and passing through the cover and perforated adjacent its upper end to receive a sealing wire.

ALEXANDER HENRY WELKER. 30
